US00D976801S

(12) **United States Design Patent** (10) **Patent No.:** **US D976,801 S**
(45) **Date of Patent:** **** Jan. 31, 2023**

(54) **TRUCK CAP**

(71) Applicant: **Truck Accessories Group, LLC**,
Elkhart, IN (US)

(72) Inventors: **Jeffrey Joal Hickey**, Sturgis, MI (US);
Donald Richard Ireland, Middlebury,
IN (US); **Terrill D. Becker**, Bristol, IN
(US); **Mitchell Austin Westra**, Granger,
IN (US); **James Dillard Fletcher**,
Elkhart, IN (US)

(73) Assignee: **TRUCK ACCESSORIES GROUP,
LLC**, Elkhart, IN (US)

(**) Term: **15 Years**

(21) Appl. No.: **29/711,962**

(22) Filed: **Nov. 4, 2019**

(51) LOC (14) Cl. **12-16**

(52) U.S. Cl.

USPC **D12/404**

(58) **Field of Classification Search**

(57) **CLAIM**

The ornamental design of a truck cap, as shown and described.

DESCRIPTION

FIG. 1 is a perspective view of a new truck cap design; FIG. 2 is another perspective view of the new truck cap design of FIG. 1;

FIG. 3 is a side view of the new truck cap design of FIG. 1; FIG. 4 is another side view of the new truck cap design of FIG. 1;

FIG. 5 is another side view of the new truck cap design of FIG. 1 with the cap door open;

FIG. 6 is a perspective view of the new truck cap design of FIG. 1 with the cap door open;

FIG. 7 is another perspective view of the new truck cap design of FIG. 1 with the cap door open;

FIG. 8 is a rear view of the new truck cap design of FIG. 1 with the cap door open;

FIG. 9 is a rear view of the new truck cap design of FIG. 1; and,

FIG. 10 is a front view of the new truck cap design of FIG. 1.

Any broken lines shown in these drawings are for purposes of illustrating portions of the design of the truck cap and form no part of the claimed design.

1 Claim, 9 Drawing Sheets
